EMBLEM FORMING DEVICE

Carl I. Oberg, Staten Island, N. Y.

Application August 5, 1952, Serial No. 302,719

3 Claims. (Cl. 41—1)

1

This invention relates to the deposition of grains of material on a surface in a predetermined form or shape, and more particularly to a device which will deposit on a surface grains of material in a predetermined pattern.

It is an object of this invention to provide a device which will deposit on a surface grains of a suitable granulated material, such as sand, in the form of a deposit of material having a predetermined shape.

It is another object of this invention to provide a figure-forming device in which a granulated material may be carried, and from which the granulated material may be deposited by the simple operation of a lever or button.

It is a further object of this invention to provide a device which may repeatedly deposit material, such as sand, on a surface in a predetermined shape.

A still further object of this device is to provide a combination of a device which deposits a granular material on a surface in a predetermined shape and a substance on the surface which retains said deposit of granular material thereon against easy removal therefrom.

It is a still further object of this invention to provide a device which will deposit abrasive, granular material, such as sand, and will be of simple construction, easily operable, and resistant to excessive wear.

These and further objects of this invention will become more apparent upon consideration of the following description, taken together with the accompanying drawings in which:

Fig. 1 is a perspective view of a device of this invention positioned above a surface upon which an emblem has been deposited according to this invention;

Fig. 2 is a longitudinal vertical section of the device of this invention shown in Fig. 1;

Fig. 3 is a horizontal section view of the device of Fig. 2, taken on line 4—4 of Fig. 2;

Fig. 4 is a bottom view of the device of Fig. 2;

Fig. 5 is a longitudinal vertical view of the device of Fig. 2 operated so as to be in a different operating position from the device of Fig. 2 so that perforations are aligned to provide for the release of granular material from within the device;

Fig. 6 is a horizontal section of a modified device of this invention;

Fig. 7 is a longitudinal vertical section of the device of this invention shown in Fig. 6, taken on line 7—7 of Fig. 6 in the direction of the arrows;

2

Fig. 8 is a horizontal section of a further modified device of this invention partly broken away;

Fig. 9 is a longitudinal vertical section of the device of this invention shown in Fig. 8, taken on line 9—9 of Fig. 8 in the direction of the arrows;

Fig. 10 is a lateral vertical section of the device of this invention shown in Figs. 8 and 9, taken on line 10—10 of Fig. 9; and

Fig. 11 is an elevation of a surface having deposited thereon a granular material according to this invention.

In general, this invention provides a box for carrying sand to be released from the box upon the operation of a releasing mechanism that deposits the sand in the form of an emblem on a surface against which the device is held.

Referring to the figures, in Fig. 1 a form of the carrying and depositing device of this invention is designated by the numeral 10. The device 10 is shown positioned above a surface 11 upon which rests an emblem 12. The device 10, as shown in Fig. 2, is composed of a casing 13 which has side walls 14, a top wall 15, and an open bottom 16.

The open bottom 16 of the casing 13 receives a plate assembly 17 which is retained in position at the bottom of the casing 13 by screws 18. The plate assembly 17 is made up of a grooved sole 19 on which is fastened a perforated screen plate 20 and felt layer 21, which is adhered to the upper surface of the perforated screen plate 20. The felt layer 21 is perforated to correspond with the perforations of the perforated screen plate 20. In turn, a sliding cut-off plate 22 is positioned on the felt layer 21. The sliding cut-off plate 22 is independent of the plate assembly 17.

As shown in Fig. 3, the sliding cut-off plate 22 is retained on the plate assembly 17 by means of a post 23 and a spring 24. The post 23 is mounted on and integral with the plate assembly 17. The spring 24 has a coil portion 25 wrapped around the post 23 and a spring arm 26 extending from the post 23 and engaging with a dog 27 mounted on the cut-off plate 22, as seen in Fig. 3. The sliding cut-off plate 22 is provided with an opening 28 to fit over the post 23 and to permit the plate 22 to reciprocate with relation to the post 23 and the rest of the device 10. At one end the plate 22 is provided with an upturned flange 29. This flange 29 is engageable with a lever 30 which has a lip 31 inserted in a slot 32 in the flange 29, as shown in Figs. 2, 3, and 5. The lever 30 extends through a slot 42 in the top wall 15. The spring 24 exerts a pressure on the cut-

off plate 22 through the dog 27. This pressure tends to move the plate 22 to the left of the device 10, as seen in Figs. 2 and 3. The cut-off plate 22 is thus held in the position shown in Fig. 2 with the lever 30 drawn against a partition 33 which extends laterally across the casing 13 and is spaced a short distance from the right end wall 14, as seen in Figs. 2 and 3. A fulcrum point 43 of the lever 30 bears against the top wall 15 of the casing 13 at the slot 42.

The sole 19 is provided with grooves 34 which define the shape of the emblem to be formed by the device 10. As shown in Fig. 4, the grooves in this embodiment outline a cruciform. The grooves 34 have walls 35 which are oblique to the perpendicular and flare outwardly from the center of the grooves 34 in a downward direction. Perforations are provided in the perforated screen plate 20. These perforations conform to the shape defined by the grooves 34. As shown in Figs. 2 and 5, the felt layer 21 is provided with perforations 37 which correspond to and combine with the perforations 36 of the screen plate 20 to provide passageways 38 from the interior of casing 13 to the grooves 34.

The cut-off plate 22 is provided with perforations 39 which correspond in configuration to the perforations 36 of the screen plate 20 and perforations 37 of the felt layer 21. In the closed position of the device 10 shown in Figs. 2 and 3, the cut-off plate 22 is positioned with its perforations 39 out of register with the passageways 38 so that the passageways are closed by the plate 22. In Fig. 5, the cut-off plate 22 is shown moved to the open position of the device 10 by the actuation of the lever 30 so that the perforations 39 are in alignment with the passageways 38 and open to the grooves 34.

The device 10 is operated to produce the emblem 12 on the surface 11 by releasing sand or other suitably granulated material through the perforations, passageways and grooves. To operate the device of this invention the casing 13 is filled with sand through a port 40. The port 40 is closed with a cover 41 which is sprung in place to retain the sand in the casing 13. As explained above, the cut-off plate 22 is normally held in a position in which its perforations 39 are closed by the felt layer 21 and its supporting screen plate 20. In this closed position the lever 30 is retained with its disengaged end elevated from the top wall 15 of the casing 13, and with its lip end drawn back against the partition 33 and retained in this position by the action of the spring 24. Upon depressing the raised end of the lever 30 the action of the lever about the fulcrum 43 moves the cut-off plate 22 to the right, as seen in Fig. 2. The cut-off plate 22 is moved into alignment with the passageways 38 and grooves 34, and when so in alignment permits the escape of the sand from the casing 13. The escaping sand fills the grooves 34 and rests on the surface 11 conforming to the grooves 34.

When the sand thus fills the grooves 34 it is molded into a shape defined by the grooves 34. In the embodiment shown in Figs. 1 to 5, the sand is molded into a crucifix emblem by the grooves 34. Upon release of the lever 30 the sliding cut-off plate 22 returns to the closed position, cutting off any further flow of sand from the casing 13, and the device 10 may be removed from the surface 11, leaving the emblem 12 formed thereon in the shape defined by the grooves 34. A sufficient quantity of sand may be retained within the casing 13 to provide for several repetitions of this

operation without refilling the casing. In each repetition the same steps of operation take place, forming identical crucifixes of perfect shape and form each time.

A modification of this invention is shown in a device 44, illustrated in Figs. 6 and 7. The device 44 is similar to the device 10 described in connection with Figs. 1 through 5 having a casing 45 made up of four side walls 46, a top wall 47, and an open bottom 48. The open bottom 48 is closed with an assembly 49 made up of a sole plate 50 and a felt layer 51. A sliding cut-off plate 52 cooperates with the assembly 49. The sole plate 50 is fastened to the casing 45 by screws 53 and retains the plate assembly 49 in the open bottom 48 of the casing 45. The felt layer 51 is supported on the sole plate 50. The sole plate 50 has grooves 54 which are formed to the shape of the emblem which it is intended the device 44 shall reproduce upon operation. The sole plate 50 also has perforations 55 penetrating through the sole plate 50. The perforations 55 are formed along the grooves 54. The felt layer 51 has perforations 56 corresponding in pattern to the perforations 55 so as to form passageways 57 through the assembly 49. The sliding cut-off plate 52 has perforations 58 in the same pattern as perforations 55 and 56. In the closed position of the device 44 the perforations 58 are blocked by the felt layer 51 and the sole plate 50. In the open position of the device 44, perforations 58 align with the passageways 57 to provide an opening from the interior of the casing 45 through the grooves 54.

The sliding cut-off plate 52 is provided with means for shifting its position horizontally across the felt layer 51 so that it can be slid from the closed position shown in the figures to an open position. The means for sliding the cut-off plate 52 is comprised of an arbor 59 which is mounted in a bearing plate 60 and a counter bearing plate 61 attached to opposite side walls 46 of the casing 45. The arbor 59 carries a cross pin 62 which is mounted perpendicular to the axis of the arbor 59. A pair of yoke members 63, extending vertically from the upper surface of the sliding cut-off plate 52, are provided with central slots 64 which receive the outer ends of the cross pin 62 so that the yoke members 63 are engageable by the cross pin 62. The arbor 59, thus connected to the cut-off plate 52, can be made to actuate the cut-off plate 52 upon reciprocation. The left end of the arbor 59, as shown in Figs. 6 and 7, is provided with a push button 65 which extends through a suitable opening 66 in the casing 45 and is manipulatable from outside of the casing 45. The arbor 59 and the push button 65 are held in the closed position shown in Figs. 6 and 7 by a spring 67 which seats against the bearing plate 60 and bears against the push button 65 to urge the push button 65 and the arbor 59 to the left, as shown in Figs. 6 and 7. The spring 67 is retained in a spring casing 68 which is integral with the bearing plate 60.

In the position shown in Figs. 6 and 7, the sliding cut-off plate 52 is shown in a closed position. The extended push button 65 may be moved inward against the spring 67, and through the cross pin 62 the arbor 59 moves the yoke members 63 to the right, as seen in Figs. 6 and 7. The perforations 58 are thus brought into alignment with the passageways 57. The casing 45 is filled with sand through a port 69 in the top wall 47. Upon aligning the perforations 58 with

the passageway 57 the sand in the casing 45 is deposited in the grooves 54 and shaped to the form of the desired emblem as determined by the shape of the grooves 54. The release of the push button 65 allows the spring 67 to return the arbor 59, cross pin 62, yoke members 63, and sliding cut-off plate 52 to the closed position, cutting off the flow of sand out of the casing. Upon removal from the decorated surface the device 44 leaves the desired emblem formed thereon.

Another modification of the device of this invention is shown in the structure illustrated in Figs. 8, 9, and 10. As described in connection with the above embodiments of this invention, a device 70 is shown having a casing 71 made up of four side walls 72 and a top wall 73. The casing 71 has an open bottom 74. The device 70 is provided with a modified means for distributing and releasing sand or other granulated material to form the desired emblem of this invention. Referring to Fig. 9, a sole plate 75 is provided with grooves 76 and perforations 77 penetrating the sole plate 75. A cut-off plate 78 slides on the upper surface of the sole plate 75 and is reciprocated by suitable means. Inward of the cut-off plate 78 in the casing 71 a screen plate 79 is mounted on posts 80 and spaced from the cut-off plate 78. The cut-off plate 78 is provided with perforations 81 in the same pattern as the perforations 77 of the sole plate 75. The screen plate 79 is likewise provided with perforations 82 in a pattern conforming to the perforations 77 and 81. The perforations 82 of the screen plate 79 are fixed directly over the perforations 77 of the sole plate 75. In the closed position of the sliding cut-off plate 78 the perforations 81 are closed by the sole plate 75. Upon operation of the reciprocating means the cut-off plate 78 is moved to the open position in alignment with the fixed perforations 77 and 82 of sole plate 75 and screen plate 79. In this position sand or other granular material retained above the screen plate 79 is free to pour through the perforations and into the grooves 76.

A partition 83 extends laterally across the casing 71 and provides a chamber 84 in which the screen plate 79 is positioned. The chamber 84 is lined with liner pieces 85 which extend along the side walls 72 of the casing 71 and are mounted on the side walls 72. The screen plate 79 is arranged to abut at its periphery the surface of the liner pieces 85 and thereby provide a seal of said chamber 84 and to allow the chamber 84 to be a repository for the sand or granular material to be deposited by the device 70. The sand or granular material which is introduced into the chamber 84 through a port 86 in the top wall 73 is supported above and away from the sliding cut-off plate 78 by the screen plate 79.

A gear box 87 is also provided within the casing 71 by the partition 83. The gear box 87 contains the means for moving the cut-off plate 78. The cut-off plate 78 is retained in slidable engagement with the upper surface of the sole plate 75 by guides 88. As seen in Fig. 8, the bulk of the cut-off plate 78 is positioned beneath the chamber 84. A tab 89 however, extends into the gear box 87. The tab 89 has mounted on it a rack 90 which is engaged by a cylindrical gear 91. A frame 92 standing upright in the gear box 87 supports a reciprocal plunger 93 which is mounted in a right angle flange 94 at the upper end of the frame 92. Seated between the flange 94 and a collar 95 on the plunger 93 a spring 96 forces the plunger downward so that in normal

position an end 97 projects through the sole plate 75 and beyond the bottom of the device 70, as seen in Fig. 9. The plunger 93 also carries a rack 98 which engages the gear 91.

In the operation of the embodiment of the invention shown in Figs. 8, 9, and 10, the device 70 is placed on a surface and pressed downward, forcing the plunger 93 upward from its normal position and turning the gear 91 with the rack 98. The gear 91 in turn moves the rack 90 which slides the cut-off plate 78 from its normal closed position into an open position. In the open position the perforations 81 of the cut-off plate 78 are in alignment with perforations 77 and 82, as explained above. In this position the sand from the chamber 84 is deposited in the grooves 76 to provide the formation of an emblem as described in connection with the above mentioned embodiments. Upon removal of the device 70 from the decorated surface, a figure in sand remains with the predetermined outline. In this embodiment the spacing of the screen plate 79 from the sole plate 75 and cut-off plate 78 allows the cut-off plate to seal in the remaining sand. It is important in this device that no sand dribble from the perforations 77 and 82 upon removal of the device 70 from the decorated surface.

As a feature of this invention the granular material may be retained on the decorated surface by a previously applied adhesive. For example, an adhesive layer 99 may be applied to a surface 100, as shown in Fig. 11. Sand 101 deposited by the device of this invention is deposited on the adhesive layer 99 and retained on the surface 100 by the adhesive layer. The adhesive layer 99 may be applied to the surface 100 in liquid form by suitable means, such as brushing or spraying. Suitable adhesion for many purposes may also be obtained by applying the adhesive in a solid viscous state from a backing of material which carries the adhesive from which it can be applied to the decorated surface. For example, pressure sensitive cellulose tape carries an adhesive. Applying the adhesive from such pressure sensitive tape to the surface and then removing the cellulose backing will leave adhesive on the decorated surface. This adhesive is relatively inconspicuous and yet will retain a granular material upon deposition from the device of this invention.

Among other advantages, this invention provides a simple means for quickly depositing a material on a surface in a predetermined shape. As shown in Fig. 1, a crucifix of sand or dust may be formed on a surface, such as the top of a casket. The deposition of the material and the formation of the resultant emblem is a simple matter with the device of this invention and can be performed with the utmost solemnity and dignity.

It is a further advantage of this invention that the operation of the device is certain and complete in its simplicity. One motion provides the desired emblem.

It is another advantage of this invention that the grooves forming the emblem have walls which, flaring outwardly and downwardly, form the material when it is deposited in the grooves into sloped piles. The material thus deposited in sloped piles retains its form after the removal of the depositing device of this invention. Therefore, at a solemn ceremony the emblem will not change shape after the removal of the depositing device.

It is another advantage of this invention that by the provision of an adhesive on the decorated surface the material is retained against removal, such as by winds and drafts of air.

It is a still further advantage of this invention that the assembly of the perforated plates according to this invention allows for a tight sealing of the granulated material within the repository chamber, and at the same time allows easy actuation of the plate with a minimum of wear.

It will be understood that the above described embodiments of this invention are set forth for the purpose of description only and that other modifications are possible within the spirit and scope of this invention, which should be limited only by the scope of the appended claims.

What is claimed is:

1. In a sand depositing device in which a casing containing sand has a stationary sole plate, the combination of a felt layer within said casing, a perforated stationary plate underlying said felt layer, a set of predetermined perforations in said felt layer and a set of perforations in said stationary plate coinciding with each other, a movable plate positioned immediately above said felt layer in said casing and in contact with said felt layer, perforations in said movable plate in said predetermined pattern, said perforations in said movable plate normally being not in alignment with said first mentioned perforations whereby said sand in said casing penetrates said movable plate and abuts against said felt layer, means in said device for maintaining said movable plate in a position with said second mentioned perforations out of alignment with said first mentioned perforations, means for moving said movable plate into position with said second mentioned perforations in alignment with said first mentioned perforations, and grooves in said sole plate coincidental with said first mentioned perforations whereby sand in said device is released by slid-

ing movement between said movable plate and said felt layer and is formed in said grooves without abrasion between said parts.

2. A sand depositing device as claimed in claim 5 1 having oblique walls in said grooves with the widest separation of said walls at the outermost edge of said grooves.
3. In a sand depositing device having a casing containing sand, the combination of a stationary sole plate forming one side of said casing, a felt liner extending around the wall of said casing at right angles to said sole plate, a movable perforated plate in said casing contiguous with said sole plate and extending across a 10 surface of said sole plate between said sole plate and an adjacent edge of said felt layer so that said adjacent edge abuts against said movable plate, a stationary screen plate positioned within said casing adjacent to but spaced from said movable plate and contiguous with said felt liner throughout its periphery, a spacing between said movable plate and said screen plate, perforations in said screen plate in a predetermined pattern, a second set of perforations in said sole 15 plate coincidental with said first mentioned perforations in said screen plate, a third set of perforations in said movable plate in said predetermined pattern normally out of alignment with said first and second perforations so constructed and arranged that the main portion of the sand in said casing normally is supported on said stationary plate and a minor portion of the sand penetrates said first mentioned perforations and rests on and is retained by said movable plate, and means for moving said movable plate whereby said sand is released from said spacing and passes through said second set of perforations in said sole plate.
